SMOKE DISPOSAL AND DRAFT INDUCING APPARATUS

Application filed December 31, 1929. Serial No. 417,774.

This invention relates primarily to improvements in adjustable smoke jacks for disposing of smoke, steam, gases and the like from locomotives in roundhouses and similar structures, and in its preferred embodiment includes means for inducing a draft through the locomotive either for the purpose of properly firing up the locomotive and generating steam in the locomotive boiler or for furnishing ventilation when men are working in the fire box of a hot locomotive.

The purpose of the invention is to provide an improved smoke jack of the vertically and longitudinally adjustable type and to combine it with a compact inexpensive and efficient draft inducing apparatus.

Heretofore jacks of this type, whether or not combined with a draft inducing apparatus, have been so constructed that they depend from trunnions or joints either at their extreme upper end or at the extreme upper end of their swinging portion with the result that the jack would normally hang vertically, and in order to bring it out of this position laterally considerable force was necessary to counteract the force of gravity. This had to be done from a remote point and the usual means employed were ropes and pulleys or links and levers, etc., none of which are practical in roundhouses. It is one of the objects of this invention to provide a jack which will be substantially balanced in any position it may occupy when applied to the stack of a locomotive, thereby cutting down, to a large degree, the need of ropes, pulleys, levers and the like for bringing it and holding it in any desired position.

Heretofore apparatus of the character described has been adapted to engage locomotives in varying longitudinal positions on the track beneath, but to my knowledge they were never adapted to move laterally with relation to the locomotive track, which is quite necessary if the apparatus has to engage the stack of a locomotive which is tilted. It is one of the objects of this invention to provide means for lateral as well as longitudinal movement of the jack in relation to the locomotive track.

Another object of the invention is to pro-

vide for engaging the jack with the stack of a locomotive from the floor of the roundhouse through a single instrumentality and to hold the lower portion of the jack in the extreme top position, when not engaged with a locomotive stack, out of the way of incoming engines.

Locomotive drafters which are combined with smoke jacks of the adjustable type consist, of course, of a fan or exhaust, an uptake pipe and an offtake or discharge pipe, and to secure the greatest efficiency in operation of the fan both the uptake and the offtake pipe should be free of all bends or elbows. To accomplish this object I use a fan of the propeller type which revolves in a horizontal plane and through which the gases pass without their course being changed. It has been attempted to accomplish this object by using a fan of the centrifugal type and mounting it with its inlet downward, but while this eliminates a bend in the intake pipe and the fan revolves in a horizontal plane it necessitates a bend in the offtake pipe in order to discharge the gases vertically into the atmosphere, thereby nullifying the advantage of the elimination of the bend in the uptake pipe. It is, therefore, one of the purposes of my invention to provide a construction wherein the gases travel through a pipe in a straight line of direction from the stack of the locomotive to the atmosphere.

A further object of the invention is to provide an improved exhaust of the combination direct and indirect induced draft type, whereby the velocity of the gases discharged by the fan draws the gases through an annular space surrounding the fan.

Another object of the invention is to provide means for protecting the motor driving the fan against the elements when not in operation.

Another object of the invention is to provide automatic means for protecting the motor from the heat of the gases when the fan is not in operation, the motor being cooled by the action of the fan when it is in operation.

Other objects and advantages of the invention will appear hereinafter.

Reference is to be had to the accompanying drawings, in which

Fig. 1 is a side elevational view (partly in section) of a preferred form of the apparatus, showing the uptake pipe in position over the locomotive stack, the dotted line position illustrating the oscillating or swinging capacity of this pipe in one direction;

Fig. 2 is an end elevational view (partly in section) thereof, showing the locomotive stack tilted, which often occurs;

Fig. 3 is a sectional view of the exhauster, oscillating casing and part of uptake pipe;

Fig. 4 is a sectional view on the line 4—4 of Fig. 1;

Fig. 5 is a sectional view of the exhauster on an enlarged scale;

Fig. 6 is a sectional view similar to Fig. 3 but with the exhauster eliminated and a counterweight added, reducing the invention to that of an improved smoke jack.

Fig. 7 is a view similar to Fig. 1, showing a modification in which a part of this invention can be carried out.

Fig. 8 is a similar view of another modification in which a part of this invention can be carried out, and

Figs. 9 and 10 are respectively an elevation and plan view of an arrangement for drafting locomotive in which the preferred form of exhauster may be used to advantage.

In the form of the invention shown in the first five figures, the smoke jack is composed, as usual, of a long tube preferably made in sections, the top section 10 adapted to receive the exhauster 11, if one is used, the supporting section 12, the main part 13 depending therefrom, and a telescoping end 14 at the bottom.

In order to counterbalance this device so that it will require little or no effort to keep it in inclined position, as indicated in dotted lines in Fig. 1, the parts above the supporting section 12 are preferably made of heavy metal, as indicated in Fig. 3, while the parts below the supporting section are made of light metal. For the purpose of adding to the weight, a ring or collar 16 is shown around the top of the section 10, or a counterweight 16^a added as in Fig. 6, and the blower 11 if used can be considered as a part of the counterbalancing means. This furnishes an important advantage because the whole device can be easily moved into inclined position and have practically no tendency to swing away from whatever position it is placed in. This avoids the use of chains, ropes, pulleys, links, etc. for holding it in some position other than normal.

For the purpose of allowing full adjustment of the lower end of the jack it is mounted on trunnions 15, as stated, which are supported in a frame 17 which itself is provided with two trunnions 18 at right angles to the trunnions 15, and resting in bearings in the

stationary support 19 on the roof 20 of the building. In this way it will be seen that not only is the jack adjustable for locomotives at different points along the track but also for those which may be tilted out of proper position.

At the bottom of the lower section the jack is provided with an adapter 21 pivoted to the member 14 on an axis at right angles to the track, and provided with a curved section 22 to avoid the entrance of air around it. This is to provide for locomotives at different points along the track as indicated in dotted lines in Fig. 1, and the globular joint prevents leakage at this point. For locomotives which are tilted on the track as indicated in Fig. 2 no globular joint is necessary on account of the limited change in stack position.

For the purpose of avoiding the complicated methods heretofore employed for raising and lowering the telescoping section 14 of the jack, I provide chains or wire ropes 23, one on each side of the jack, connecting the section 14 with a quadrant 24. This supports the section in any desired position. This quadrant is mounted on a frame 25 having arms extending into position to be secured to the jack in a firm stationary position and rigidly mounted. Turning with the quadrant is an arm 26, provided preferably with a counterweight 27 and adapted to be manipulated from the floor of the building by a rod 28 pivoted to its lower end. This rod 28 not only is capable of being raised and lowered to perform the opposite operation on the telescoping section 14, but it also can be used to swing the jack out of vertical position as may be desired.

Referring to Fig. 2 it will be seen that by pulling down on the rod 28 the telescoping section 14 will be raised. The upper part of this section is provided with spring latches 14^a which engage over an annular rib 13^b on the jack 13 when the telescoping section is raised high enough, so that this section is held out of the path of incoming engines. When it is desired to lower the telescoping section, it is first raised a little higher by pulling down on rod 28 and then allowed to drop, its weight carrying the spring latches by the annular rib, after which it may be lowered to any desired position by raising the rod 28. To move the jack longitudinally with the track it is only necessary to move the rod 28 in the direction desired. To move the jack laterally in relation to the track towards the left, the rod 28 is moved in that direction, the part of the rod extending above the pivot 28^a engaging with a stop 26^a on the arm 26. By pulling down on the rod 28 the jack has a tendency to move laterally to the right in relation to the track unless checked by moving the rod to the left, and therefore it is only necessary to allow the jack to follow this natural tendency if it is desired to move it that

way. It will therefore be seen that I have provided for engaging the jack with the stack of a locomotive from the floor of the round-house and for holding the lower portion of the jack out of the way of incoming engines through a single instrumentality, namely the rod 28.

It will be understood that the jack can be used simply for carrying away the smoke under natural draft without any exhauster, as indicated in Fig. 6, in which case the construction is the same with the omission of the blower. For the purpose of counterbalancing the parts below the supporting section 12, counterweights 16^a preferably located opposite each other are provided which may be adjustable to secure perfect balance.

The exhauster may be a steam jet or air jet blower, but for the sake of efficiency I prefer a power driven fan. It is shown as mounted in the center of the section 10 on a vertical axis and operated by a motor 30 located in a casing 31 centrally placed. Instead of using a motor to drive the exhauster any other driving means may be used as, for instance, a fluid turbine. The fan of the exhauster is located in a casing 32 also centrally placed, and supported from the inner wall of the section 10 by radial arms, thus forming therewith an annular space through which the gases may pass at all times. The casing 32 is provided with doors 33 which are adapted to be opened by the force of the draft behind them, but normally will lie inclined downward, as indicated in dotted lines, to protect the exhauster from the elements. The velocity of the gases discharged through the casing 32 causes part of the gases to pass upwardly through the space between the casing 32 and the wall of the section 10, thereby increasing the efficiency of the exhauster.

The casing 31 is shown as provided with an inlet 31^a and a small blower 34 is adapted to direct a blast of cold air through the inlet 31^a and its motor adapted to be connected with a source of power by a thermostat 35. If the heat gets too high, the thermostat will expand and connect the motor of the blower 34 with its source of current, and then, as long as the temperature is too high, cold air will be blown into the motor casing 31 to keep the motor 30 in a safely cool condition.

When the exhauster is in operation it draws air through the inlet 31^a and around the motor, thus keeping the motor cool, but when it is not in operation and the apparatus is used merely as a smoke disposal device there may not at all times be enough cooling air entering the casing 31 for keeping the motor in a safely cool condition and therefore the blower 34 will supply the deficiency.

In the form shown in Fig. 7 the upper end 65 of the uptake pipe is provided with an elbow

40 which terminates and extends towards the inlet of an exhaust fan 41 having a motor 42 outside the casing where it is exposed to the cooling influence of the atmosphere. The casing of the exhaust fan is supported by suitable brackets and fastened to the roof of the building. The elbow 40 is pivoted on a shaft 43 substantially co-axial with the inlet of the exhaust fan, said shaft being supported above the roof of the building and having a counter-weight 44 provided on an arm so that the uptake pipe is counterbalanced.

In the form shown in Fig. 8, the lower part of the device is the same, and the jack extends materially above the roof of the building, has a lateral outlet extending and terminating towards the inlet of an exhaust fan 46, and is supported by a shaft 45 substantially co-axial with the shaft of the exhaust fan 46. Here the top of the jack is provided with a pivoted cover 47 normally held open by a counterweight 48. When the blower 46 is started up it will draw the air currents from the main jack into the blower casing and discharge them into a pipe 49. In this case the cover 47 will close by the suction created in the jack.

In the form shown in Figs. 9 and 10, the preferred form of exhauster, as shown in Figs. 3 and 5, is employed in a different type of jack in which the top of it extends upwardly above the blower, and is provided with a lateral discharge 50 into a vertical pipe 51 from which it discharges at a point well above the roof. The jack is provided with a rotatably mounted intake pipe 53 on a roller support 52, the intake pipe thus being adapted to swing about a vertical pivot through any space within approximately 90° as indicated in Fig. 10. When not in use it is adapted to be swung back against the wall of the building as shown in dotted lines in that figure. It is also adapted to swing around a horizontal pivot 59 and it is held up by a counterweight 58 supported by a cable 57 or the like. The horizontal intake pipe 53 has a telescoping cap 56 slidable on rollers 55 and adapted to fit over the locomotive smoke stacks.

In this way it will be seen that the adjustment is sufficient for all purposes, and that wherever the locomotive is located, within a limited area, the cap 56 can be moved to register with it. The blower 11 in this case may be the same as shown in Fig. 5, and is so indicated. This shows the application of this invention to an old form of jack for the same purpose as the other figures.

The construction of the exhauster is not claimed herein by itself as it is covered by my copending application Serial No. 180,018, filed March 31, 1927, patented May 17, 1932, No. 1,858,581.

Although I have illustrated and described

only four forms of the invention I am aware of the fact that changes can be made therein by any person skilled in the art without departing from the scope of the invention as expressed in the claims. Therefore, I do not wish to be limited to the forms shown, but what I do claim is:—

1. As an article of manufacture, a smoke jack suspended to swing, having the part above the point of suspension made to substantially counterbalance the part below the point of suspension. 10
  2. In a roundhouse equipment, the combination of an exhauster, an uptake pipe having a pivotal connection which permits the pipe to swing so that the lower end of the pipe may be adjusted longitudinally in relation to the track below, and means extending above said pivotal connection to counterbalance the pipe below said pivotal connection. 15
  3. A smoke jack for roundhouses having means for pivotally suspending the same at an intermediate point between its intake and its outlet, the portions on either side of said point substantially balancing each other, and means for swinging the smoke jack on its point of suspension longitudinally in relation to the track below. 20
  4. A smoke jack for roundhouses having means for suspending the same at an intermediate point between its intake and its outlet which permits the jack to be adjusted longitudinally and laterally in relation to the track below, the portions on either side of said point substantially balancing each other. 25
  5. In a roundhouse equipment, the combination of an exhauster and a smoke jack having means for pivotally suspending the same at an intermediate point between its intake and its outlet, the portions on either side of said point substantially balancing each other. 30
  6. In a roundhouse equipment, the combination of an exhauster and a smoke jack supporting the exhauster and mounted in a manner allowing it to swing laterally in relation to the track below. 35
  7. In a smoke disposal and draft inducing apparatus, the combination of a conduit adapted to convey the gases from the locomotive to the atmosphere, an exhauster within the conduit comprising a fan rotatably mounted and a casing surrounding the fan and spaced inside of the conduit, the outer wall of said casing forming with the inner wall of the conduit a passageway for the gases. 40
  8. In a smoke disposal and draft inducing apparatus, the combination of a conduit adapted to convey the gases from the locomotive to the atmosphere, an exhauster within the conduit comprising a fan rotatably mounted and a casing surrounding the fan and spaced inside of the conduit, the outer wall of said casing forming with the inner wall of the conduit an annular space through 45
- which part of the gases are driven, caused by the velocity of the gases discharged by the fan of the exhauster when the fan is running. 50
9. In a locomotive drafter, the combination with a conduit, of an exhauster within said conduit, and covering means for the exhauster to protect it against the elements. 70
  10. In a smoke jack, the combination with a conduit, an exhauster in the conduit, a motor for the exhauster in the conduit, a casing for the motor to protect it from direct contact with the smoke and gases passing through the jack, and means for automatically introducing air from outside the conduit into said casing at a predetermined temperature of the gases in the conduit. 75
  11. In a locomotive drafter, the combination with a conduit, of an exhauster at the upper end of the conduit, and covering means for the exhauster to protect it against the elements. 80
  12. In a locomotive drafter, the combination with a conduit, of an exhauster mounted within said conduit in such a manner as to form a space between said exhauster and the inner wall of the conduit, and covering means for the exhauster to protect it against the elements. 85
  13. In a locomotive drafter, the combination with a conduit, of an exhauster within said conduit, and covering means for the exhauster to protect it against the elements when said exhauster is not in operation. 90
  14. In a smoke jack, the combination with a conduit pivotally mounted, of a telescoping section at the bottom and a depending rod connected with the jack for swinging it about its pivot and for raising and lowering the telescoping section. 95
  15. A smoke jack for roundhouses having means for suspending the same at an intermediate point between its intake and its outlet which permits the jack to swing so that the lower end of the jack may be adjusted laterally in relation to the track below, the portions on either side of said point substantially balancing each other. 100
  16. In a roundhouse equipment, the combination of an exhauster, a smoke jack, and means for suspending the jack at an intermediate point between its intake and its outlet, permitting the jack to swing so that the lower end of the jack may be adjusted longitudinally in relation to a track below, the portions on either side of said point substantially balancing each other. 105
  17. In a roundhouse equipment, the combination of an exhauster, a smoke jack, means for pivotally suspending the jack at an intermediate point between its intake and its outlet, the portions on either side of said point substantially balancing each other, and means for swinging the smoke jack on its point of suspension longitudinally and laterally in relation to a track below. 110

18. In a roundhouse equipment, the combination of an exhauster, a smoke jack, and means for suspending the jack at an intermediate point between its intake and its outlet permitting the jack to swing so that the lower end of the jack may be adjusted laterally in relation to a track below, the portions on either side of said point substantially balancing each other. 70
19. In a smoke disposal and draft inducing apparatus, the combination of a conduit adapted to convey the gases from a locomotive to the atmosphere, an exhauster within the conduit comprising a fan rotatably mounted and a casing surrounding the fan and spaced inside of the conduit, the outer wall of said casing forming with the inner wall of the conduit a passage through which the gases may be discharged by natural draft. 75
20. In a smoke disposal and draft inducing apparatus, the combination of a flue for conducting the hot gases and an exhauster, said exhauster comprising a fan and a casing surrounding the fan located inside of said flue, and a motor for actuating the fan exposed to the cooling influence of the atmosphere. 80
21. In a smoke jack, the combination of a conduit pivotally mounted, a telescoping section at the bottom, a frame secured to the conduit, a quadrant pivoted on said frame, a flexible connection on the quadrant connected with the telescoping section for raising or lowering it, an arm on the quadrant for operating it, and an operating rod pivotally depending from said arm. 85
22. In a smoke jack, the combination with a conduit, of an exhauster mounted in the upper end of the conduit, an inlet from outside the conduit to the motor of the exhauster, a thermostat near the motor, and a ventilating blower adapted to force a draft through said inlet and connected to be started into operation by the action of the thermostat, when the temperature gets too high. 90
23. In a roundhouse equipment, the combination of an exhauster, and a smoke jack supporting the exhauster and mounted in a manner allowing it to swing longitudinally in relation to the track below. 95
24. In a smoke jack, the combination with a conduit pivotally mounted, of a depending rod for swinging the conduit about its pivot and connected with the conduit in such a manner as to be capable of moving with the conduit and in the same direction of the conduit. 100
25. In a smoke jack, the combination of a conduit pivotally mounted, a telescoping section at the bottom, means for raising or lowering the telescoping section and an operating rod pivotally depending from said means. 105
26. In a roundhouse equipment, the combination of an exhauster and a smoke jack 110
27. In a smoke jack, the combination with a conduit mounted upon a universal joint and a depending rod connected with the conduit for swinging it about the pivots of the universal joint. 115
28. A smoke jack having a telescoping section, means for raising and lowering said section and means associated with the jack and the telescoping section capable of maintaining said section in an elevated position. 120
29. A smoke jack having a telescoping section, means for raising and lowering said section and means on the smoke jack cooperating with means on the telescoping section for maintaining said section in an elevated position. 125
- In testimony whereof I have hereunto affixed my signature.
- FRANS H. C. COPPUS. 130
